UNITED STATES PATENT OFFICE.

JAMES BALDWIN, OF MANCHESTER, NEW HAMPSHIRE.

LOOM-SHUTTLE.

SPECIFICATION forming part of Letters Patent No. 323,554, dated August 4, 1885.

Application filed February 14, 1885. (No model.)

To all whom it may concern:

Be it known that I, JAMES BALDWIN, of Manchester, in the county of Hillsborough, State of New Hampshire, have invented certain new and useful Improvements in Loom-Shuttles, of which the following is a description sufficiently full, clear, and exact to enable any person skilled in the art or science to which said invention appertains to make and use the same, reference being had to the accompanying drawings, forming a part of this specification, in which—

Figure 1 is a reduced vertical longitudinal section of a shuttle provided with my improvement, the spindle being represented as depressed and a portion of the body of the shuttle broken off; Fig. 2, a like view, the spindle being represented as raised and in elevation; Fig. 3, a vertical longitudinal section of the spindle detached; Fig. 4, a like view showing a modification of the bobbin-spring, and Fig. 5 a reduced vertical longitudinal section showing a shuttle of the same general class, the spindle being represented as depressed and a portion of the body of the shuttle broken off.

Like letters of reference indicate corresponding parts in the different figures of the drawings.

My invention relates more especially to means for preventing the bobbin from being "knocked off" or becoming accidentally detached from the spindle of the shuttle.

Shuttles have heretofore been provided with springs, the ends of which are fixed in sockets at both ends of the spindle. In that case the spring is not permitted to expand and contract in its sockets, and it is liable to be broken when the bobbin is placed on the shuttle.

Shuttle-spindles have also been heretofore provided with a bobbin-retaining spring having one end fixed in a socket at the free end of the spindle, the other end being loose in a socket at the lower end of the spindle, and the spindle being provided with a second spring interposed between it and said bobbin-retaining spring to cause the latter to press outward against the bobbin. This construction is comparatively cumbersome and expensive.

The object of this invention is to overcome the difficulties above set forth, and provide a

spring which will yield with great facility when a bobbin is placed on the spindle.

The nature and operation of the improvement will be readily understood by all conversant with such matters from the following explanation, its extreme simplicity rendering an elaborate description unnecessary.

In the drawings, A represents the body of the shuttle; B, the spindle; C, the bobbin, and D the spring. The spindle is provided with a catch or head, x, and is pivoted or journaled in the body A on the pin i in the usual manner. A hole or socket is formed in the rear of the head x on its upper side, as shown at d, a corresponding hole or socket being formed in the shank or heel of the spindle, as shown at l. An outwardly-curved or elliptic spring, E, is disposed on the upper side of the spindle B, the ends of the spring being inserted in the sockets d l, and its body of such length as to prevent it from being readily detached therefrom.

In the use of my improvement the spindle is elevated, as shown in Fig. 2, and the bobbin passed on over it in the usual manner until the top or outer end of the same has passed the head x, when the expansive action of the spring E will cause it to move laterally and its end to engage with said head, thereby locking it in position on the spindle and preventing it from being accidentally detached therefrom in a manner which will be readily obvious without a more explicit description.

It will be understood that the sockets d l are of sufficient depth to permit the spring E to be sufficiently depressed to enable the bobbin C to be readily inserted and removed as required.

A modification of my improvement is shown in Fig. 4, which consists in making the spring E in the form of a double ellipse or bending it inwardly at its center, as seen at t, to form the sections z z, this shape being preferable when the spindle is very long, or when more tension is required on said spring than can be readily attained with the single ellipse shown in Figs. 1, 2, and 3.

In Fig. 5 a shuttle-spindle is shown which is now in common use, and therefore not claimed herein. Said spindle is provided with a curved spring, H, one end of which is firmly secured in the head of the spindle and the

other inserted in a hole in the shank or heel J, said hole being curved upwardly and opening out through said shank beneath the spring D.

The spring H is elongated and bent at its outer end to fit the hole in the shank J, and extends upwardly through said shank sufficiently to engage the spring D, said last-named spring causing the body of the spring H to act on the bobbin and keep it in engagement with the head x when the spindle is depressed. When the spindle is elevated, and the end of the spring D passes into the notch or depression v in the shank J, the bent end of the spring H passes out of contact with the spring D, thereby relieving the tension on the spring H and permitting the bobbin to be removed from the spindle.

Although the device last described, and as shown in Fig. 5, possesses some advantages over other well-known methods of securing or locking the bobbin to the spindle, in that it is to a certain extent automatic in its action, it is defective or objectionable in the following respects: First, the spring, where it passes through the hole in the shank J, requires great care in fitting, and to be constantly oiled to have it work freely; second, as there is no pressure or tension on the spring H when the spindle is elevated, careless workmen are liable to withdraw the bobbin to such an extent as to leave it resting on or extending over the head x as the spindle is depressed; third, the spring H, being loose at its outer end, is liable to become bent and spoiled, and is comparatively expensive to replace, and, fourth, it is comparatively expensive to construct.

My invention is designed to obviate these difficulties and objections, and to that end I make use of the sockets d l and the spring E, said sockets being of sufficient depth to permit the spring to be readily depressed as the bob-

bin is crowded on over it, and said spring of such a length as to remain in the sockets when the bobbin is removed, this form of construction being exceedingly simple, cheap, durable, and effective. 45

A longitudinal groove, h, is formed on the upper side of the spindle B to receive the spring E as it is depressed by the bobbin, and also to assist in keeping said spring in proper position on the spindle, the sockets d l being formed at the ends of said groove. The groove may, however, be omitted, the sockets d l and spring E being so formed as to prevent said spring from getting out of place. The spring E and sockets d l may also be placed beneath the spindle or at either side thereof, if preferred.

Having thus explained my invention, what I claim is—

1. A shuttle-body provided with a spindle 60 pivoted thereto, said spindle having at its opposite ends sockets, which are closed at their outer ends, in combination with a longitudinally-expansible spring the ends of which are loose in said sockets, said spring being adapted 65 to expand longitudinally under compression into either socket and to expand laterally without withdrawal of its ends from said sockets, substantially as described.

2. A shuttle-body provided with a spindle 70 having a longitudinal groove, said spindle having sockets at each end of said groove, in combination with a spring having two waves or curves, the central depression of said spring resting in said groove and its ends being free 75 to reciprocate in said sockets, substantially as described.

JAMES BALDWIN.
